CLAIM

The ornamental design for a baby chair, as shown and described.

DESCRIPTION

FIG. 1 is a perspective view of a baby chair showing my new design;

FIG. 2 is a front view thereof;

FIG. 3 is a rear view thereof;

FIG. 4 is a left view thereof;

FIG. 5 is a right view thereof;

FIG. 6 is a top view thereof; and,

FIG. 7 is a bottom view thereof.

The broken lines immediately adjacent to the shaded areas represent unclaimed boundaries of the design. The broken line showing of the remainder of the baby chair is for illustrative purposes only and forms no part of the claimed design.
